UNITED STATES PATENT OFFICE.

MARTIN A. GREEN, OF PHILADELPHIA, PENNSYLVANIA.

STEAM-ENGINE.

1,160,069.

Specification of Letters Patent.

Patented Nov. 9, 1915.

Application filed January 20, 1915. Serial No. 3,261.

To all whom it may concern:

Be it known that I, MARTIN A. GREEN, a citizen of the United States, and a resident of Philadelphia, in the county of Philadelphia, and State of Pennsylvania, have invented a new and useful Improvement in Steam-Engines, of which the following is a specification.

My invention is an improvement in steam engines of the type known as center discharge or uni-directional flow steam engines, that is, that type of engine in which the steam enters at the ends of the cylinder through admission valves and follows the piston practically the entire length of the stroke and exhausts through a center exhaust port which surrounds the entire periphery of the cylinder. The steam in such engines once it enters the cylinder, never 20 turns on its path within the cylinder and hence the name, uni-flow steam engines.

The object of this improvement is to provide improved means which is controlled automatically by the steam without the aid 25 of mechanism connecting to the moving parts of the engine to control and produce the proper compression when the engine is running non-condensing and condensing.

In the drawings:—Figure 1 is a longitudinal vertical section through the cylinder of an engine constructed in accordance with the invention, Fig. 2 is an enlarged longitudinal section of the piston, Fig. 3 is a bottom plan view of the piston, Fig. 4 is a section on the line 4—4 of Fig. 2, looking in the direction of the arrows adjacent to the line, and Fig. 5 is an end view of the piston.

As is known with an engine of the character in question running non-condensing (95% of the steam engines in use so running) 18 to 20% clearance is necessary to provide for the volume of steam remaining in the cylinder at the end of each stroke, and which must obviously be compressed by the 45 return stroke of the piston. The object of the present invention is to provide for the exhaust and removal of this steam from the cylinder, and this is brought about by means of a double headed auxiliary valve in the piston, and operating in conjunction with a storage chamber also in the piston, the chamber having a port at each end of the piston, and the valves coöperating with the ports to alternately open and close the ports,

the valves being operated at the end of the 55 stroke of the piston in each direction.

The engine in the present instance comprises a cylinder consisting of a cylindrical body 1, closed at its ends by heads 2 and 3, and admission ports 4 and 5 are arranged 60 at the ends of the cylinder for admitting the steam thereto. The steam is admitted to a chamber 6, formed adjacent to the cylinder and extending longitudinally thereof through a port 6^a, and the chamber is adapted 65 to connect at each end with the ports 4 and 5. Valve seats 7 and 8 are formed at the ends of the chamber between the chamber and the ports 4 and 5, and valves 9 are provided for coöperating with the seats. 70

Each valve has secured thereto a stem 10, the valve being connected to the stem near its lower end, and each stem engages at its lower end an opening in a nipple 11 on the cylinder coaxial with the adjacent seat. On 75 the opposite side of the valve from the nipple each stem 10 passes through a guide sleeve 12, held in a guide 13, supported above the seat, each of the guides 12 being approximately cylindrical, and having an annular 80 groove for receiving a packing ring 14 to assist in preventing the escape of the motive fluid through the guide around the sleeve. The lower end of each sleeve has a frusto-conical head as shown, and an annular rib 85 or shoulder is formed between the head and the body of the sleeve, each shoulder engaging a similar shoulder in the guide, to limit the upward movement of the sleeve.

A wheel or roller support 15 is connected 90 with the outer end of each stem, and a wheel or roller 15 is journaled on each support. Each of the rollers 15 is above the valve operating stem 16, and the stem is provided with enlargements 17 and 18, for engaging 95 between the roller 15 and a roller 15^a journaled on the guide on the opposite side of the stem from the adjacent roller 15. A coil spring 19 normally presses each roller support toward the cylinder, acting to hold the 100 valve closed, and the tension of each spring may be regulated by means of adjusting mechanism 20, coöperating with the outer end of the guide. The valve operating mechanism forms no part of the present invention, and for this reason is not more closely described. The stem 16 is connected to one end of a lever 21, pivoted interme-

diate its ends to a support 22 and operated by the piston in any usual or desired manner.

At its center a portion of the cylinder is offset outwardly to form an annular chamber 23 at the center of the cylinder, and extending entirely around the same, and opening into an exhaust chamber 24 below the cylinder. From this chamber 24 the steam may pass to the atmosphere in any desired or suitable manner. The piston 24 is hollow or chambered as shown more particularly in Figs. 1 and 2, and at the center of the heads 25 and 26 of the piston hubs 10 are provided, the hub 27 of the head 25 being counterbored at the outer face of the cylinder as indicated at 28. The hub 29 of the head 26 is internally threaded, and the piston rod 30 is reduced at the point where 15 it enters the piston through the head 26, the said head being that adjacent to the cross head.

At the junction of the reduced portion with the main portion of the piston rod, the 20 rod is externally threaded as shown at 31, to engage the internally threaded hub 29, and at the hub 27 the rod is again reduced as shown at 32 to engage the said hub. The end of the piston rod is externally threaded 25 as shown at 33, this threaded portion extending into the counterbore 28, and a nut 34 is threaded on to the threaded portion 33 within the counterbore. The head 26 bears against the annular shoulder formed between the reduced portion and the body of 30 the piston rod, and the annular shoulder formed at the inner end of the reduced portion 32 bears against the inner face of the head 25. The piston is thus locked from 35 movement with respect to the piston rod in either direction.

At its lowest portion a chamber 35 is formed in the piston, the said chamber having no communication with the interior of 40 the piston, being separated therefrom by a web 36, and bearings 37 are formed at the junction of the web with the heads, the said bearings being in alinement as shown. The bearings are at the inner sides of radial 45 extensions 38 from the chamber 35, and at the outer side of each extension a port 39 is provided, the said ports being circular and coaxial with the bearings 37. The outer end of each port is beveled or flared as 50 shown at 40, to form a valve seat, and a frusto-conical valve 41 coöperates with each seat. The valves 41 have hubs 42 on their inner faces, the said hubs being internally threaded and being engaged by threaded 55 portions at the end of a stem 43.

The outer face of each valve, as shown more particularly in Fig. 5, has a series of annular grooves 44, and the periphery thereof is also provided with one or more grooves 60 45. The valve stem 43 is of such length

that the valves cannot both seat at the same time. When one valve is seated, the other valve is unseated, and the movement of the stem is limited in either direction by the engagement of the valves with their seats. The ports 39 are for placing the chamber 35 in communication with the interior of the cylinder, and at the chamber the wall of the piston is provided with a number of openings 46 for permitting the exhaust steam held in the chamber 35, to pass into the exhaust chamber 24, when the said openings 46 come into register with the chamber.

The ports 46 are arranged intermediate the ends of the piston, and between the side walls of the chamber 35 formed by the web 36. On the outer side of each of the side walls above mentioned, openings or ports 47 are provided for permitting the interior of the piston to drain. The piston has water 35 grooves 48 at each end, and when the valves 41 are closed, their outer faces will be flush with the outer faces of the heads of the piston.

It will be noted from an inspection of Fig. 1 that the relative dimensions of the piston and cylinder are such that the entire length of the piston may be received in those portions of the cylinder on opposite sides of the annular recess or chamber 23. That is, at the end of the stroke of the piston away from the cross head, the outer surface of the head 26 is flush with one wall of the chamber 23, while at the end of the stroke of the piston toward the cross head the outer surface of the head 25 is flush with the other wall of the said chamber.

The operation of the improved engine is as follows:—When the valve 9 at the port 7 is opened to permit the motive fluid to flow from the chamber 6 by way of the port 4 to the outer end of the cylinder, the piston will be driven toward the cross head. When the piston starts toward the cross head, the parts occupy the position shown in Figs. 1 and 2, that is, the valve 41 at the outer end of the cylinder is closed, and the valve 41 adjacent to the chamber 23 is open. When now the piston starts toward the cross head, as soon as it covers the annular passage between the cylinder and the chamber 23, the exhaust to the atmosphere is closed, and any steam remaining in the inner end of the cylinder would necessarily be compressed were there no outlet for the same. However the valve 41 at the inner end of the piston is open and any exhaust steam that may remain in the inner end of the cylinder passes through the port 39 into the chamber 35.

As the openings or ports 46 pass over the central exhaust such exhaust steam as may be in the chamber 35, will pass out into the exhaust chamber 24. It will be noted that the openings 46 leading from the chamber 130

35 of the piston do not extend to the ends of the piston, the openings stopping at a distance of from two to three inches from the ends. This is for the purpose of permitting the reservoir or auxiliary chamber 35 in the piston to be cut off from the center exhaust before the piston reaches the end of its stroke, so that pressure will be created in the chamber 35 sufficient to shift 5 the valve stem 43 and the valves 45 before the piston reaches the end of its stroke in either direction. As soon as the chamber 35 is cut off from the exhaust, pressure begins to generate in the chamber, and the cutoff 10 is so set that there will be sufficient pressure in the chamber 35 to shift the valves to close that in advance and open that in rear, and to prevent any contact of the valves with the cylinder, when coöperating 15 with the pressure in front of the piston and in front of the advance valve.

Even when the engine is shut down and steam turned off and the engine is running of its own momentum neither valve will 20 touch the cylinder heads. Before the stem 43 is moved however, the central exhaust is opened by the piston uncovering at least a portion of the same, and when the valve stem is moved to seat the valve at the inner 25 end of the piston the central exhaust is fully opened. When the piston moves outward the valve 41 at the outer end of the piston will be opened so that any exhaust steam that may be trapped in the outer end 30 of the cylinder may pass into the chamber 35 and out through the openings 46 into the exhaust chamber. Thus that steam slightly above atmospheric pressure that does not exhaust is provided for, passing into the 35 chamber 35, and no clearance is necessary at the ends of the cylinder.

The operation is entirely automatic, no attention being required, nor is there any complicated mechanisms to get out of order, 40 neither is there springs to break or to become rusted. At the end of the stroke of the piston in each direction a large exhaust passage is opened, sufficient to care for practically all of the steam. That steam which 45 does not have sufficient pressure to cause it to exhaust will pass out by way of the chamber 35 and the openings 46. These openings 50 are open until just before the end of the stroke of the piston, that is, until just before 55 the moment when the valve stem 43 is shifted. Any excess of steam that may not be able to pass out through the openings 46, will be cared for in the chamber 35. The grooves 44 and 45 of the valves 41 are compression 60 grooves to permit the formation of air or steam cushions to make the valves seat noiselessly and to eliminate noise.

The openings 46 do not, as before stated, 65 extend to the ends of the piston, the series terminating a sufficient distance from the

end, so that the communication between the chamber 35 and the exhaust chamber 24 will be cut off just before the piston reaches the end of its stroke in each direction. Thus the end of the cylinder toward which 70 the piston is moving will hold sufficient steam to provide a compression sufficient together with that in the chamber 35, to shift the valve mechanism, that is, to close the valve adjacent to the end toward which 75 the piston is traveling. At this same moment the piston uncovers the central exhaust, thus relieving the pressure on the valve that would otherwise resist the shifting of the valve mechanism. 80

Preferably the wall of the piston at the chamber 35 is perforated between the packing ring 48 at each end, and sundry of the openings at the ends may be closed by plugs as indicated at 49. By means of these plugs 85 the exact amount of compression necessary may be provided. Hence in the construction the piston serves not only as an exhaust valve but in addition serves for what may be practically termed a sliding valve, 90 the compression being increased or diminished by the plugs 48. The engine can for this reason be run with a minimum of clearance and without back pressure, so that the full compression of the steam may be 95 utilized, and practically the same results may be attained with an engine running non-condensing as though the engine were run condensing.

It will be seen that in carrying out the 100 invention no additional ports are necessary, nor is there any change in the external appearance of the engine, the valve mechanism being self-contained within the piston. A feature of importance is, that were the 105 engine built and set to run non-condensing, in order to provide for its running condensing, it is only necessary to unscrew one of the auxiliary valves 41, remove the washers shown at 50 in Fig. 2, and return the 110 valve to place, turning the valve to take the place of the washer removed, and space the valves in such manner that they will both be seated, thus closing the auxiliary ports. These washers are of an aggregate thickness 115 corresponding to the length over all of the valve stems and valves, over that of the piston, and when the washers are removed, and the valve heads 41 turned inwardly to the extent of their movement the valves 41 will fit closely to their seats at each end of the piston, and the engine is in shape to run condensing. That is, by removing the washers as above described the piston is made a 120 closed piston without openings at either 125 end.

Because of the openings at the bottom or under side of the piston there is more or less pressure upward, which practically carries the piston, preventing wear on the bot- 130

tom of the cylinder, while at the same time it makes a perfect system of lubrication in the bottom of the cylinder where the wear occurs. No packing rings are used, the 5 grooves 48 being water grooves, preventing leakage in this manner.

I claim:—

1. In a reciprocating steam engine, the combination with the cylinder having at 10 each end an inlet port and provided at its center with an annular exhaust chamber encircling the cylinder and having an annular exhaust passage communicating with the chamber, a hollow piston within the cylinder and of a length to uncover the annular exhaust passage at each end of its stroke, said piston having at the under side thereof a chamber and a series of radial openings leading from the chamber for registering with the exhaust passage as the 15 piston moves thereover, said piston having a port at each end of the chamber, for guided movement in the piston, a valve connected with each end of the stem, said stem being of greater length than the piston to prevent the simultaneous closing of the 20 valves, the radial openings of the chamber in the piston being spaced from the ends of the piston to cut off the auxiliary chamber 25 from the exhaust before the piston reaches the end of its stroke to provide sufficient pressure within the chamber and in front of the piston to shift the valves, each valve having annular grooves on its periphery and 30 on its outer face.

2. In a reciprocating steam engine, the combination with the cylinder having inlet ports at its ends, and provided at its center with an annular exhaust chamber communicating with the cylinder throughout its 40 extent, a piston within the cylinder, and of a length to uncover the exhaust passage at each end of its stroke, said piston having at the under side thereof a chamber and a 45 series of openings leading from the chamber for registering with the exhaust passage, said piston having a port at each end thereof communicating with the chamber, a valve for coöperating with each port, a stem connecting the valve and of greater length than the piston to prevent the simultaneous seating of the valves, said piston having means for guiding the stem to constrain it to move parallel with the axis of the piston.

3. In a reciprocating steam engine, the combination with the cylinder having inlet ports at its ends, and provided at its center with an annular exhaust chamber communicating with the cylinder throughout its 55 extent, a piston within the cylinder, and of a length to uncover the exhaust passage at each end of its stroke, said piston having at the under side thereof a chamber and a series of openings leading from the chamber 60 for registering with the exhaust passage,

said piston having a port at each end thereof communicating with the chamber, a valve stem mounted to move longitudinally of the piston and parallel with the axis thereof and of greater length than the piston, and a valve secured to each end of the stem for closing the adjacent port when the stem is moved away from the port, each valve being adapted to be moved into closed position by the pressure in advance of the piston when the piston nears the end of its stroke in that direction.

4. In a reciprocating steam engine, the combination with the cylinder having inlet ports at its ends and having a central exhaust port, a piston within the cylinder and of a length to uncover the exhaust port at each end of its stroke, said piston having a chamber extending longitudinally thereof and having a port at each end of the piston, 80 the piston having openings leading from the chamber and adapted to register with the exhaust port, a valve for each port, and a stem connecting the valves and of greater length than the piston to prevent the simultaneous closing of the valves, the radial openings of the chamber in the piston being spaced from the ends of the piston to cut off the auxiliary chamber from the exhaust before the piston reaches the end of its stroke 95 to provide sufficient pressure within the chamber and in front of the piston to shift the valves.

5. In a reciprocating steam engine, the combination with the cylinder having inlet ports at its ends and having a central exhaust port, a piston in the cylinder and having a chamber extending longitudinally thereof and having a port at each end of the piston, the piston having openings for placing the chamber in communication with the exhaust, a valve coöperating with each port for closing the same, and a rigid connection between the valves of greater length than the piston to prevent the simultaneous seating of the valves, the radial openings of the chamber in the piston being spaced from the ends of the piston to cut off the auxiliary chamber from the exhaust before the piston reaches the end of its stroke to provide sufficient pressure within the chamber and in front of the piston to shift the valves.

6. In a reciprocating steam engine, the combination with the cylinder having inlet ports at its ends, and the piston in the cylinder, the piston having a chamber and having a port for the chamber at each end of the piston, a valve coöperating with each port, a rigid connection between the valves and of greater length than the piston to prevent the simultaneous seating of the valve, said cylinder having a central exhaust, and the piston having openings leading from the chamber and adapted to register with 130

the exhaust, each valve being adapted to be closed and to open the other valve by the pressure in the end of the cylinder toward which the said valve is moving when the piston nears the end of its stroke.

6 7. In a reciprocating steam engine, the combination with the cylinder having inlet ports at its ends, and a central exhaust, a piston in the cylinder and adapted to uncover the exhaust at each end of its stroke, said piston having a chamber and a port for the chamber at each end of the piston, the piston having openings adapted to register with the exhaust as the piston passes over the same, and means controlled by the pressure in the cylinder for simultaneously closing the port at the forward end of the piston and for opening the port at the rear end of the piston as the piston nears the end of its stroke in each direction.

10 8. In a reciprocating steam engine, the combination with the cylinder having end inlet ports and a central exhaust port, of a piston having a port at each end and a chamber with which the ports communicate, and having an exhaust for the chamber, and means for alternately closing the ports, said means being controlled by the pressure in the end of the cylinder toward which the piston is moving to close the forward valve and to open the rear valve as the piston nears the end of its stroke.

15 9. In a reciprocating steam engine, the combination with the cylinder having inlet ports at its ends and a central exhaust, a piston in the cylinder and adapted to uncover the exhaust at each end of its stroke, the piston having a chamber and ports leading from the chamber to the opposite ends of the piston, and having openings adapted to register with the exhaust as the piston passes over the same, a valve coöperating with each port, a stem connecting the valves, the piston having bearings for the stem, and 20 said stem being of greater length than the length of the piston to normally hold one valve open when the other is closed, said valves and stem being shifted near the end of the stroke of the piston in each direction by the trapped steam in the end of the cylinder toward which the piston is moving to close the adjacent valve and open the remote valve.

25 10. In a reciprocating steam engine, the combination with the cylinder having inlet ports at its ends and a central exhaust, a piston in the cylinder and adapted to uncover the exhaust at each end of its stroke, the piston having a chamber and ports leading from the chamber to the opposite ends of the piston, and having openings adapted to register with the exhaust as the piston passes over the same, and means operated by the trapped steam at the end of the cylinder 30 toward which the piston moves for simultaneously closing the adjacent port and opening the remote port.

11. In a reciprocating steam engine, the combination with a cylinder having end inlet ports and an intermediate exhaust port, a piston in the cylinder and adapted to uncover the exhaust port at each end of its stroke, the piston having an auxiliary chamber and a port at each end of the chamber opening at the adjacent end of the piston, said piston having a port leading from the chamber and adapted to register with the exhaust port as the piston passes over the same, a valve stem mounted to move longitudinally of the piston at the ports and 35 between the same, a valve at each end of the stem adjustable longitudinally of the stem, said stem being of a length to permit the valves to be seated simultaneously or to prevent seating simultaneously.

40 12. In a reciprocating steam engine, the combination with a cylinder having inlet ports at its ends and a central exhaust, the piston in the cylinder and adapted to uncover the exhaust at each end of its stroke, 45 said piston having a chamber provided with ports adapted to communicate with the exhaust in succession as the piston passes over the exhaust, said piston having ports opening from the chamber at the ends of the piston, and a valve for each port, a rigid connection between the valves and having guided movement longitudinally of the piston, and being of greater length than the piston to prevent the simultaneous closing 50 of the valve, the ports adapted to register with the exhaust of the cylinder being spaced from the ends of the piston to cut off the chamber from the atmosphere before the piston reaches the end of its stroke in either 55 direction to provide for sufficient compression in front of the piston at each end of its stroke to operate the valves.

60 13. In a reciprocating steam engine, the combination with a cylinder having inlet ports at its ends and a central exhaust, the piston in the cylinder and adapted to uncover the exhaust at each end of its stroke, said piston having a chamber provided with ports adapted to communicate with the exhaust in succession as the piston passes over the exhaust, said piston having ports opening from the chamber at the ends of the piston, and a valve for each port, a rigid connection between the valves and having 65 guided movement longitudinally of the piston, and being of greater length than the piston to prevent the simultaneous closing of the valve, said ports being spaced from the ends of the piston to cut off the chamber 70 from the exhaust just before the piston reaches the end of its stroke in either direction.

75 14. In a reciprocating steam engine, the combination with the cylinder, having inlet 80

ports at its ends and a central exhaust, of a combined piston and exhaust valve, said piston being chambered and having ports leading from the chamber to the ends of the piston, and having ports adapted to communicate with the exhaust of the cylinder as the piston moves thereover, and arranged to cut off the chamber from the exhaust before the piston reaches the end of its stroke in either direction to provide for a degree of compression in front of the piston, valves coöperating with the ports at the ends of the piston,

and a rigid connection between the valves and having guided movement in the piston and of a length to prevent the simultaneous closing of the valve, said valves opening outward from the piston and being adapted to be opened and closed by the pressure in front of the piston. 15
